TRANSFER DEVICE FOR GUIDING STRAND AS IT IS CONTINUOUSLY UNWOUND FROM SPOOLS

Benson F. Bachus, Westchester, Ill., assignor to Western Electric Company, Incorporated, New York, N.Y., a corporation of New York

Filed Aug. 30, 1955, Ser. No. 531,444

2 Claims. (Cl. 242--128)

This invention relates to a device for guiding strand as it is unwound continuously from spools at different locations and more particularly to a device having a strand guiding element shiftable from one to another of a pair of supply stations for guiding the strand from spools at these stations.

An object of the invention is to provide a strand guiding device having a movable element for guiding the strand from spools at a pair of stations and having means for supporting and yieldably maintaining the element in a pair of positions aligned with the spools and permitting movement of the element from one position to the other by the strand as the unwinding of the strand is transferred from one spool to another.

A device illustrating certain features of the invention may include means for supporting a pair of spools of interconnected strand at a pair of stations in laterally spaced relation to each other, and means for supporting a strand guiding arm in two operative positions above the spools at the stations and for oscillatable movement about a tilted axis for guiding one end of the arm from one position above one of the spools to the other position above the other spool to guide the strand while it is being unwound sequentially from the spools without interruption. As the arm is moved from one operative position to the other the tilted mounting thereof causes the end of the arm to swing through an arc and to rise from a predetermined low level above one spool to a higher level at a point intermediate its two spool positions and then fall to said predetermined level above the other spool so that the arm is yieldably held by gravity in either of its two operative positions and as the unwinding of the strand is transferred from one spool to another the arm is moved by the strand from one position through the center or high point of travel and is carried by gravity and its inertia through the rest of its travel to its other operative position.

Other objects and advantages of the invention will become apparent by reference to the following detailed description and the accompanying drawings illustrating a preferred embodiment thereof, in which

Fig. 1 is a plan view of the device for guiding strand as it is being unwound sequentially from a pair of spools;

Fig. 2 is a front view of the device;

Fig. 3 is a side view of the device;

Fig. 4 is an enlarged plan sectional view of a portion of the strand guiding device taken along line 4-4 of Fig. 2; and

Fig. 5 is an enlarged fragmentary vertical sectional view of the device taken along line 5-5 of Fig. 1.

Referring to the drawings, 15 represents a base for supporting a pair of spools or reels 17 having a continuous wire 18 and having retractable members 19 for positioning the spools in predetermined locations or stations 20 and 21 while the wire is being unwound therefrom and fed into a pulp machine for applying insulation thereto. Flyers are placed on the upper head of the spools to tension the wire and cause uniform unwinding thereof. The

2

flyers comprise a sheet metal disc 22 with a downwardly turned curved flange, a post 23 for supporting an arm 24 for rotation, a grooved roller 25 on the end of the arm for guiding the wire, and a spring 26 for pressing the arm 24 against the disc to provide a drag for tensioning the wire 18. The wire, as it is unwound from a spool 17 and tensioned by the flyer, moves upwardly through a ring 27 fixed to one end of an arm 28 of a wire guide and automatic transfer device 30 which is mounted in a predetermined position above the base 15 and the spools 17 thereon. At its other end the arm 28 has a hub 31 which is mounted for oscillatable movement on an upwardly directed pin 32. Ball bearings 34 (Fig. 5) are provided to reduce the friction between the pin 32 and the hub 31. The pin 32 is secured to a supporting member 33 which has a cylindrical lug 35 extending horizontally from one end thereof into one end of a tubular horizontally disposed arm 36 on the upper end of a standard or post 37 extending upwardly from the base 15. The supporting member 33 may be angularly adjusted about a horizontal axis extending through the lug 35 to tilt the pin 32 to any desired angle from the vertical, and the supporting member 33 may be locked in its selected angular position by a lock screw 40 threadedly mounted in the tubular arm 36 for clamping the lug 35 against movement. The supporting member 33 is positioned so that the axis 41 of the pin 32 is disposed and is angularly adjustable in a vertical plane positioned midway between the spools 17 and the stations 20 and 21, and the arm 28 is adapted to be oscillated about the axis 41 and the pin 32 through a limited movement on opposite sides of the vertical plane into two operative positions. A pair of stop screws 45 mounted on the supporting member 33 in angularly spaced relation to each other are engageable with a depending stop finger 47 on the arm 28 to stop the arm in two operative positions with the guide rings 27 above and in substantial vertical alignment with the spools 17. The tilted axis of oscillation 41 causes the free end 40 of the arm 28 to travel through an arc 49 (Fig. 2) having a vertical rise and fall with the low points of the arc being above and in alignment with the spools at the operative positions of the arm 28 so that as the arm is moved from one operative position to the other the free end thereof is caused to rise from its low point over one spool to a high point intermediate its two operative positions and fall to its other low point at its other operative position above the other spool. The force of gravity serves to yieldably maintain the arm in its operative positions. Thus, the arm may be moved from one position through its high point and gravity will cause it to be moved to its other position and yieldably maintain it therein. A pulley 50 is mounted on the free end of the arm 28 above the ring 27 for receiving the wire 18 during its upward movement from a spool 17, and a pulley 51 is mounted on a bracket 52 fixed to and extending upwardly from the other end of the arm 28 for receiving the wire from the pulley 50 and directing toward the axis 41. A stationary pulley 54 mounted on a bracket 55 secured to the upper end of the pin 32 cooperates with the pulley 51 for guiding the strand upwardly a short distance in substantial alignment with the axis 41 and for guiding the strand for horizontal movement therefrom. In the operation of the device, as the wire 18 is being unwound from a spool 17 at station 20 it is tensioned by the flyer and is guided upwardly through the guide ring 27 and over the pulley 50 toward the axis 41 and is then directed upwardly and laterally to a pulp machine (not shown) for processing, and while the wire is being unwound from this spool, a full spool of strand is loaded onto the station 21 and the leading end of the wire thereof is bonded to the trailing end of the wire of the spool at

station 20 to produce a continuous wire. The loose portion of joined wire extending between the reels is tucked under a spring clip 60 on the base 15 and is yieldably held there to apply a slight tension thereto. When the wire has been unwound from the spool at station 20 and the unwinding is being transferred to the spool at station 21, the tension of the wire exerts a lateral pull on the arm 28, causing it to move away from its low point at its operative position at station 20 through the center or high point between the stations, whereupon gravity and the inertia of the arm will cause the arm to continue its movement to its other low point and its other operative position above the spool at station 21. The empty reel may then be removed from station 20 and a full reel placed thereon, after which the strands on the two reels are interconnected as explained above and the cycle of operation is repeated, with the strand causing the arm 28 to be shifted from its operative position above a spool at station 21 into its operative position above the reel at station 20 in response to the transfer of the unwinding of wire from the spool at station 21 to the spool at station 20. From the above description it will be seen that the arm 28 is supported in either of its two low operative positions in alignment with spools of wire at the two stations for guiding the wire therefrom and that the arm is yieldably maintained in either of these two positions and is capable of being moved by the strand from a low point at one operative position through the intermediate high point of travel and caused to move down to its other low point at its other operative position in response to the transfer of the unwinding of the strand from one spool to the other. In apparatus where full spools of wire are loaded at one station, as for example station 21, and then transferred to the other station 20 and removed therefrom when empty, the arm 28 is moved with the reel from station 21 to station 20 by the pull of the wire 18 thereon.

The angular position of the axis 41 of oscillation of the arm 28 may be adjusted to vary the component of gravitational force tending to keep the arm in either of its two operative positions so that it will be sufficient to yieldably maintain the arm in its two operative positions but will not exceed the force exerted by the pull of the wire on the arm for shifting it from one position to another when the unwinding of the wire is transferred from one spool to another.

It is to be understood that the above-described arrangements are simply illustrative of the application of the principles of this invention. Numerous other arrangements may be readily devised by those skilled in the art which will embody the principles of the invention and fall within the spirit and scope thereof.

What is claimed is:

1. In a device for guiding strand as it is unwound from spools, the combination of mounting means for supporting a pair of spools of interconnected strand at a pair of stations in laterally spaced relation to each other on opposite sides of a vertical plane midway therebetween, a strand-guiding arm, an adjustable supporting member, means for pivotally mounting said strand-guiding arm on

said supporting member for oscillatory movement about a first axis, said supporting member having a cylindrical element projecting laterally therefrom, a standard on said mounting means having a cylindrical recess concentric with a horizontal axis disposed perpendicular to said vertical plane for receiving said cylindrical element and supporting said supporting member for pivotal movement about said horizontal axis and with said first axis positioned in said vertical plane so that said supporting member may be adjusted to locate said first axis in various angular positions in said vertical plane, a screw threadably mounted in said standard and engaging said cylindrical element for securing said supporting member in adjusted position on said standard with said first axis disposed obliquely to a vertical axis, and means for stopping the movement of said strand-guiding arm about said first axis with the free end of said arm in predetermined operative positions in alignment with the spools in said stations, the angular position of the first axis being so arranged to cause the free end of said strand-guiding arm to be raised from a predetermined level at its operative positions to a higher level at an intermediate position in said vertical plane and lowered to said predetermined level as said arm is swung from one operative position to another whereby said arm is yieldably held by gravity in its operative positions.

2. In a device for guiding strand as it is unwound from spools, the combination of mounting means for supporting a pair of spools of interconnected strand at a pair of stations in laterally spaced relation to each other on opposite sides of a vertical plane midway therebetween, an adjustable supporting member, a strand-guiding arm pivotally mounted on said supporting member for oscillatory movement about a first axis, a standard on said mounting means, means for pivotally mounting said supporting member on said standard for movement about a horizontal axis perpendicular to said vertical plane and with said first axis positioned in said vertical plane and obliquely to a vertical axis whereby said supporting member may be adjusted to vary the angular position of said first axis in said vertical plane, means for securing said supporting member in adjusted position on said standard, and means for stopping the movement of said strand-guiding arm about said first axis with the free end of said arm in predetermined operative positions in alignment with the spools in said stations, the angular position of the first axis being so arranged to cause the free end of said strand-guiding arm to be raised from a predetermined level at its operative positions to a higher level at an intermediate position in said vertical plane and lowered to said predetermined level as said arm is swung from one operative position to another whereby said arm is yieldably held by gravity in its operative positions.
